CLAIM

The ornamental design for a fidget slider as shown and described.

DESCRIPTION

FIG. 1 is a front, right, and top perspective view of a fidget slider, showing my new design;

FIG. 2 is a rear, left, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, right, and top perspective view showing the fidget slider in a position of use; and,

FIG. 10 is another front, right, and top perspective view showing the fidget slider in a position of use.

The broken lines depict portions of the fidget slider that form no part of the claimed design.
